ATTORNEY.

UNITED STATES PATENT OFFICE.

THOMAS AUGUSTUS MARTIN, OF COVINGTON, KENTUCKY.

DEVICE FOR HANDLING, LIFTING, OR SUPPORTING INVALIDS OR THE LIKE.

No. 841,702.

Specification of Letters Patent.

Patented Jan. 22, 1907.

Application filed November 6, 1905. Serial No. 286,117.

To all whom it may concern:

Be it known that I, THOMAS AUGUSTUS MARTIN, a citizen of the United States, residing at Covington, in the county of Kenton and State of Kentucky, (whose post-office address is 61 Powell street, Covington, Kenton county, Kentucky,) have invented certain new and useful Improvements in Devices for Handling, Lifting, or Supporting Invalids, Patients, or the Like, of which the following is a specification.

It is the object of my invention to provide a new and improved device for the purpose of moving or handling helpless or afflicted persons, cripples, or invalids with comfort to the patient and ease to the nurse or attendant.

My invention consists in providing a flexible sheet upon which the patient is adapted to lie and a carrying-frame, with straps or connections between the sheet and carrying-frame which are substantially shorter at the head end than at the lower end of the sheet, so that when the frame is raised the head end of the sheet may be first raised for raising the body of the patient into substantially upright position, after which the further raising of the frame will bring the lower straps or connections into lifting action and, in connection with the lifting action of the upper connections and sheet, will support the patient on the sheet in sitting position and enable him to be thus swung or carried on the supporting-frame to another chair or bed or other device, when the supporting-frame can be lowered for seating or reclining the patient in the chair, bed, or other device; and my invention consists, further, in so arranging the connections that the patient may be readily turned or shifted while prostrate. For raising the carrying-frame I prefer to employ a rope, chain, or cable, in connection with a pulley, block, and tackle or winch or other device for multiplying the raising force of the power applied. By means of my improved device the patient may be easily turned, shifted, raised, or transported by the exertion of little power, and the invention will be more fully understood from the following description and claims and from the drawings, in which latter—

Figure 1 is a perspective view of my improved device shown occupied by a patient. Fig. 2 is a plan view of the carrying-sheet with its supporting connections. Fig. 3 is a central longitudinal section of the same on

the line *x* of Fig. 2, and Fig. 4 is a perspective view of the lower reinforce-plate. Fig. 5 is a detail view in perspective, showing how the long supporting-straps can be instantly shortened to substantially the length of the short supporting-straps.

1 represents the sheet, which is preferably of canvas, ticking, or other soft material and may be upholstered, if desired. The sheet at its head end is provided with a connection 2 at each side thereof and at its lower end with a connection 3 at each side thereof. The connections 3 are preferably substantially longer than the connections 2 for purposes herein-after explained. Each of these connections 70 is preferably capable of adjustment to length, as by being separated intermediate of its length for forming a pair of strands 4 5, one of the strands having a buckle 6 secured thereto, the tongue 7 of which is adapted to 75 be selectively inserted into holes 8 of the other of said strands. The head end of the sheet preferably has extensions 9 and the lower end of sheet extensions 10, to which the strands 5 are secured, forming part of the respective connections 2 3, the head end being preferably cut rounding, as shown at 11.

12 is a carrying-frame with which the connections 2 3 are adapted to be releasably engaged. Thus the carrying-frame may be 85 provided with hooks 13 and the connections with rings 14, adapted to be engaged into the hooks for connecting the sheet with the carrying-frame. The carrying-frame is adapted to be raised and lowered in suitable manner 90 for rendering the raising or lowering of the same when the patient is supported in the sheet easy for the nurse or attendant. I have shown such means as comprising a post 15, which may be of any desirable length to 95 suit the height of the room in which the device may be used and is journaled at its top in a ceiling-plate 16 and at its bottom in a floor-plate 17. An arm 18, suitably braced, extends from the post and at its outer end 100 has a pair of pulleys 19 20, journaled therein, a pulley-block 21 being connected with the frame 12, as by means of a hook 22 taking into an aperture 23 in the frame. A rope 24 or other suitable flexible raising connection 105 has its end attached to a hook 25 on the pulley-block and takes over the pulley 19, the pulley in the pulley-block, the pulley 20, then passes along the arm 18 and over a pulley 26, and thence to a drum 27, upon which 110

it is adapted to be wound. For turning the drum I prefer to connect it with a gear 28 on a shaft 29, the gear 28 being meshed by a gear 30 on a shaft 31, the shafts 29 31 being journaled in a suitable gear-frame 32, each of said shafts having squared ends for the reception of an operating - handle 33. A ratchet and pawl 34 may also be provided for limiting the descent of the frame 12 whether or not the sheet or patient be supported thereby.

If it is desired to raise the patient, the supporting-frame is lowered to enable the connections 2 and 3 to be connected therewith. The head connections being shorter than the lower connections, power will first be exerted upon these head connections when raising the supporting-frame, thereby raising the body of the patient toward or into an upright position, when the lifting power will also be exerted upon the lower connections and the patient raised bodily into sitting position, so as to be suspended from the carrying-frame above the bed, when he can be easily swung from the bed to a chair, bed, or other device—as a commode, for instance—and gently lowered thereon. When replacing the patient into the bed, he can be gently lowered into sitting position upon the bed, when his body may be gently reclined back into lying position without strain upon the patient, nurse, or attendant.

The adjustments in the connections 2 and 3 permit the patient when in sitting position to be normally inclined farther backwardly or forwardly, as may be desired, and additional adjustment for the purpose may be provided by additional hooks 13' on the carrying-frame with which the rings 14 may be selectively engaged.

The sheet 1 is preferably flexible. In order to afford additional ease to the patient when raising or lowering the same, the sheet may be provided with detachable reinforcing-strips at the back and under the hips of the patient. For this purpose I provide the head end of the sheet with a pocket 35, adapted to receive a stiffening-board 36, and provide the lower end of the sheet with a pocket 37, adapted to receive a stiffening-board 38, the stiffening-board 38 preferably having a recess 39 arranged to take about the opening 40, provided for obvious reasons. When it is desired to raise the patient, the stiffening-boards will be temporarily slipped into the pockets and the patient then raised, these boards preferably extending from side to side of the sheet for preventing crowding or drawing of the sheet about the patient.

The sheet may also serve the purpose of a chair in which the patient may rest.

If it is desired to turn the patient upon his side or to roll the patient upon the bed, one or both of the connections 3 may be provided with a shortening device, as a hook 41 and a ring 42, adapted to be interengaged for the purpose of providing additional adjustment to said connections for quickly bringing the connections at one side of the sheet to substantially equal length, the connections at 70 said one side of the sheet being connected with the one side of the carrying-frame, the other side of said sheet remaining free of connection with said frame, whereupon when the frame is raised the patient will be turned or rolled with little exertion by the attendant. When the hook 41 and ring 42 are interengaged, the part of the connection 3 between the same will form a loosely-hanging loop 43.

Having thus fully described my invention, 80 what I claim as new, and desire to secure by Letters Patent, is—

1. In a device of the character described, the combination of a flexible sheet having comparatively short straps extending therefrom at its head end and comparatively long straps extending therefrom at its foot end, a supporting-frame, means for releasably securing said straps to said supporting-frame, a hook and eye on each of said long straps 90 for instantly reducing them to substantially the length of said short straps, and means for raising and lowering said supporting-frame, substantially as described.

2. In a device of the character described, 95 the combination of a flexible sheet having comparatively short straps extending longitudinally therefrom at its head end and having a pocket at its head end opening toward its head edge, a removable stiffening-plate 100 received by said pocket, said flexible sheet having comparatively long straps extending laterally therefrom at its foot end, and a pocket at its foot end opening toward its foot edge, said flexible sheet further having an opening 40, a removable stiffening-plate received by said last-named pocket, a supporting-frame, means for releasably securing said straps to said supporting-frame, and means for raising and lowering said supporting-frame, substantially as described.

In testimony whereof I have signed my name hereto in the presence of two subscribing witnesses.
